UNITED STATES PATENT OFFICE.

JAMES B. KNICKERBOCKER, OF INDIANAPOLIS, INDIANA, ASSIGNOR TO THE KNICKERBOCKER GAS REGULATOR COMPANY, OF SAME PLACE.

AUTOMATIC PRESSURE-REGULATOR.

SPECIFICATION forming part of Letters Patent No. 427,516, dated May 6, 1890.

Application filed October 28, 1889. Serial No. 328,431. (No model.)

To all whom it may concern:

Be it known that I, JAMES B. KNICKERBOCKER, of Indianapolis, county of Marion, and State of Indiana, have invented certain new and useful Improvements in Automatic Pressure-Regulators; and I do hereby declare that the following is a full, clear, and exact description thereof, reference being had to the accompanying drawings, in which like letters refer to like parts.

My invention relates to the construction of automatic regulators for gas, water, or steam, and will be understood from the following description.

15 In the drawings, Figure 1 is a side view, the diaphragm and its connections being in section. Fig. 2 is a longitudinal section of the valve, valve-chamber, and the connected pipes. Fig. 3 is a longitudinal section through the 20 valve-chamber and pipes, showing the construction of the valve and the openings which admit the gas into the diaphragm. Fig. 4 is a top view of Fig. 6. Fig. 5 is a bottom end view of the same. Fig. 6 is a side view of 25 the valve, showing the outlet-openings. Fig. 7 is an end view of the cap *c*, which closes the valve-chamber. In Fig. 2 the position of the valve and inlet and outlet pipes is reversed as compared with Fig. 1.

30 In detail *ip* is the inlet-pipe, which is screwed into the flange *f*, which abuts against a similar flange *f'*, formed on the body of the regulator, the flanges being united by bolts, as shown in Fig. 1. Within the chamber sur-

35 rounding the valve is a semicircular plate *p*, which divides the inflowing current of gas into two substantially equal volumes or parts, and these pass around in the direction indicated by the arrows and through the inlet- 40 ports *po po'* into the valve *k*.

45 *br* is a cross-brace for connecting and strengthening the valve-walls, which are formed in the shape shown in Fig. 6, tapering slightly and having openings on opposite sides to permit the passage of the gas, the outlet-openings being much larger than the inlet-openings, which are also opposite each other, as shown in Fig. 2.

50 *op* is the outlet-pipe, which is connected to the regulator-body in the same manner as the inlet-pipe heretofore described.

55 *ks* are the raised seats, which afford bearings for the valve, the valve-stem passing through the shell in the manner shown in Fig. 3. To the upper end of this stem is connected a lever *l'*, secured in place by a nut on the threaded end of the valve-stem at 5. A boss is formed on the lower end of the valve, against which the end of a screw *s* abuts, and about this screw-bolt and the boss is coiled a 60 spring *sp*, whose tension holds the valve in its seat and makes it take up its own wear. The set-screw *s* aids in this, but is only intended to be added for use in case of well or other unusual pressure.

65 *c* is a cap, which closes the valve-chamber, and when screwed down in its place a tension is brought upon the spring *sp*, and the valve is held firmly in its seat and prevented from any downward movement, making its bearing snug at all times. The lever *l'* is connected at 5 to the valve-stem, as shown in Fig. 1, and its other end is pivoted at 4 to a nut *n'*, which works upon the threaded end of a connecting-rod *cr*, which is in turn pivoted at 3 to the curved lever *l*, which is further pivoted at 1 to an upright *u*, secured to the diaphragm-case. The lever *l* is also centrally pivoted at 2 to the stem of the diaphragm.

70 *h* is a hood, which is mounted on the diaphragm-stem and covers the boss formed on the upper half of the diaphragm-frame *df*, through which the stem *st* passes, and its object is to protect the diaphragm from dirt or 75 water. The diaphragm itself consists of a sheet of rubber or other suitable material *g*, secured between the two halves of the diaphragm-case, carrying a metal disk *d* upon its top, the disk and sheet held together firmly 80 between a flange formed on the diaphragm-stem *st* and a nut which works on the stem above the metal disk *d*. This disk provides a firm backing for the rubber sheet *g* over nearly its entire area, and as the valve will 85 continue its rotary movement even after the pressure is cut off the diaphragm will rise until the metal disk *d* strikes the top of the diaphragm-case and all rupture by undue expansion of the rubber sheet is thus prevented.

90 *o o* are openings through the diaphragm-

case from below, through which the gas passes up into the diaphragm-chamber. When the valve is closed, the edges of the inlet-ports pass very slightly beyond the bearing of the 5 valve-seats—sufficiently, however, to make a tight joint; and in case these edges should wear away, by turning the nut n' and raising that end of the lever l^2 it is obvious that the valve is slightly rotated so as to make an increase 10 in the lap of the valve upon the valve-seats, thus remedying the difficulty occasioned by the wearing away at the edges.

The gas being admitted into the diaphragm-chamber from below, and pressure being simply 15 on the under side thereof, it is readily seen that all water and other moisture carried into the diaphragm-chamber will drain away by gravity, leaving the diaphragm dry and free from rust or corrosion, preventing 20 any moisture from collecting thereon and freezing therein, affecting its operation. This arrangement I believe to be peculiar to my diaphragm, and it is an important one.

My device operates as follows: The gas 25 passing into the inlet is divided by the plate p into equal parts, and enters through the ports po po' into the interior of the valve k , and thence out through the larger openings of the valve in the direction of the arrows 30 and through the outlet op and also up through the passage n into the diaphragm, so that the pressure upon the diaphragm is equivalent to that in the chamber between the valve and outlet-pipe. The gas entering into the diaphragm-chamber from below presses on the 35 under side of the diaphragm and tends to lift it, and as it rises it carries the stem st up with it, and this bears against the lever l and tends to raise its outer end. This lever is 40 also pivoted at 1 to the upright u , and, curving around, passes back, and on its outer end is a counter-weight. When, therefore, the pressure of the gas exceeds that of the weight, which may be adjusted on the lever l to carry 45 any pressure desired, this weighted lever will rise, and through the connecting-rod cr will operate the lever l^2 and turn the valve, partially closing it, cutting off the gas, and will continue to do this until the pressure of the 50 weight balances or exceeds that of the gas, when a contrary movement opens the valve, and gas will be let into the valve from the inlet-pipe, which is the high-pressure side of the regulator. When the gas-pressure becomes 55 less than the weight, the contrary movement takes place, the weight falls, and the valve is gradually opened, according to the demand on the outlet side. This action of the machine is therefore entirely automatic, 60 and whatever be the pressure from the main pipe the pressure on the other or low-pressure side of the regulator will never exceed that of the weight w at whatever point this is set upon the lever l .

65 In the drawings, Figs. 1 and 2, the parts are shown in proper position when the valve is wide open, and if the pressure from the in-

let side shall cease entirely the weight will drop and completely close the valve, (the diaphragm becoming entirely inactive,) but in an 70 opposite direction from that in which it is closed when the machine is in operation, and when thus closed by the failure of pressure the valve must be opened again by raising the lever by hand if its immediate operation 75 is desired.

The advantages of my device may be summed up as follows:

First. Only such parts of the valve are used as are necessary to do the work required, and the friction is thereby greatly reduced, which is a very important point with valves of this kind, while at the same time such parts are retained in use as to make every part perfectly tight without the aid of any packing 85 whatever.

Second. In case any dirt or other matter should pass through the regulator it will accumulate inside the valve and can do no injury, inasmuch as it cannot be deposited upon the valve-seats, these being entirely protected, for the valve never leaves its seat, but rotates back and forth, being held in position by the strong spiral spring and set-screw, giving it 90 at all times an even tension and making it 95 self-adjusting to all wear.

Third. Another advantage is the peculiar shape of the body of the machine, which, while simple in construction, yet secures the benefit of a large area or space of gas from 100 the inlet side, which is found to be necessary in case of a sudden fall in the pressure from the source of supply, and by admitting this pressure into the valve from two directly-opposite sides and in currents of equal pressure 105 and volume all friction upon the valve is prevented from that source, making it a perfect balance and producing a regulator that will deliver exactly the same pressure on the outlet side of the machine, whether it is a pressure of one or five hundred pounds on the inlet side.

Fourth. The valve-seats are raised, making the bearing of the valve thereon simple, and this enables the valve to fit more closely and 115 work with greatly reduced friction, and there is little or no possibility of the parts suffering from corrosion or gumming.

Fifth. The connection of the valve to the diaphragm by which the former is operated is made on the outside of the machine, and these connections are adjustable, so that by the use of the thumb-nut the valve can be reset from the outside even while in operation and can even be entirely replaced in case of wear with little trouble. By the use of the curved lever upon the top of the regulator the weight 120 can be adjusted more accurately to the number of pounds or ounces of pressure required.

Sixth. It is well known that gas freezes only 130 in its expansion, and as the expansion in my device takes place upon the inside of the valve it cannot therefore affect the movement of the valve in its seat or interfere with the

working of the machine, as in the case of ordinary valves, where the freezing of the gas will tend to fasten the valve to its seat.

Seventh. The diaphragm-case is so constructed that the diaphragm itself cannot be sprung or ruptured, as both the rubber sheet and the metal backing, of which the diaphragm is composed, rest firmly against the solid surface of the top of the case when the machine is closed, and the gas, being admitted to the diaphragm-chamber through the small openings, cannot wear or affect the diaphragm itself.

Eighth. The construction of the regulator is such that the valve shuts off tight, and it will remain so, thus avoiding the waste of gas so common with other devices.

What I claim as my invention, and desire to secure by Letters Patent, is the following:

1. In a pressure-regulator, a hollow conical valve having narrow ports on the inlet side set opposite each other across the diameter and wider openings on the outlet side, such valve having bearings upon narrow raised seats formed upon the wall of the valve-chamber, substantially as shown and described.

2. An automatic pressure-regulator comprising a valve-chamber having inlet and outlet connections, a hollow conical valve seated therein upon raised bearings, and a circular deflecting-plate located therein adjacent to the mouth of the inlet-pipe for dividing the current from the source of supply into two equal parts, substantially as shown and described.

3. An automatic pressure-regulator comprising a valve-chamber, inlet and outlet connections, a conical hollow valve seated therein upon raised bearing-seats, such valve having narrow inlet-ports and wider outlet-ports, a diaphragm-case connected to the outlet side of the valve-chamber, openings for admitting the gas from such valve-chamber into the diaphragm-chamber, a diaphragm composed of a thin sheet of flexible material with a metal backing covering its greater area carried upon a stem, and a lever mechanism pivoted at the top of such stem and carrying a counter-weight at one end, the other end of such lever connected to a secondary lever mounted upon the valve-stem, whereby the valve-action is controlled by the degree of pressure upon the diaphragm, substantially as shown and described.

4. An automatic pressure-regulator comprising a valve-chamber with suitable inlet and outlet connections, a conical hollow valve having inlet and outlet ports seated therein upon narrow raised bearings for reducing the friction, a deflecting-plate located adjacent to the mouth of the inlet and adapted to divide the current of the inflowing gas into two substantially equal volumes for admission into the interior of the valve through its inlet-ports, an automatic controlling mechanism connected to the valve-chamber on the outlet side composed of a diaphragm-chamber, a

diaphragm inclosed therein to which the gas is admitted directly from below through small openings, a lever, and weight mechanism connected to the stem, upon which the diaphragm is carried, whereby the pressure of the gas upon the diaphragm is adapted to be equalized by the action of the weight, substantially as shown and described.

5. An automatic pressure-regulator comprising a hollow conical valve having inlet and outlet ports seated upon narrow bearings in the valve-chamber and having the usual inlet and outlet pipe connections, a deflecting-plate located adjacent to the inlet-mouth, whereby the inflowing gas is divided into two substantially equal volumes and admitted into the valve in opposing currents, and a diaphragm connected with the valve-chamber on the outlet side, such diaphragm carried upon a stem which is in turn pivoted to a lever carrying a counter-weight whose rise and fall is adapted to counteract the pressure of the gas upon the diaphragm and control the valve-action, substantially as shown and described.

6. In a pressure-regulator, a valve-chamber, a conical hollow valve seated upon raised seats formed therein, and a lever connected at one end to the projecting end of the valve-stem and pivoted at its other to a nut which works upon the threaded end of a connecting-rod, whereby the valve may be adjusted in its seat, so as to increase the lap thereof in case of wear, substantially as shown and described.

7. An automatic pressure-regulator comprising a valve-chamber having inlet and outlet connections, and a hollow conical valve seated therein having narrow inlet-ports located at opposite sides of its diameter with respect to each other and wider outlet-ports, such valve held in its seat by the pressure of a coiled spring operating against the larger end of the valve and the inside of the cap that closes the valve-chamber, all combined substantially as shown and described.

8. An automatic pressure-regulator comprising a valve-chamber having inlet and outlet pipe connections, a conical hollow valve having bearings upon narrow raised seats of corresponding shape and provided with narrow inlet and wider outlet ports, such valve held to its seat by the pressure of a spring between the cap of the valve-chamber and the larger end of the valve, and a lever connected to the valve-stem at one end and pivoted at the other to a nut adjustable upon a rod connected with a lever carrying a counter-weight, whereby the valve may be slightly rotated in its seat, so as to increase the width of its bearings in case of wear at the edges of the ports, substantially as shown and described.

9. An automatic pressure-regulator comprising a valve having suitable inlet and outlet pipe connections, and a conical hollow valve seated therein and held normally in its seat by the pressure of a spring operating against the end of the valve and held between the

valve and the valve-chamber, such valve rotatable in its seat, so as to increase the lap in case of the wearing away of the edges of the ports by means of a lever, one end connected to such valve, the other pivoted to a nut working upon a rod connected to an auxiliary lever carrying a counter-weight and pivoted to a diaphragm mechanism connected to the valve-chamber on the outlet side thereof,

all combined substantially as shown and described.

In witness whereof I have hereunto set my hand this 8th day of October, 1889.

JAMES B. KNICKERBOCKER.
